William C. Sommer.
by N. DuBois his Atty,

UNITED STATES PATENT OFFICE.

WILLIAM C. SOMMER, OF SPRINGFIELD, ILLINOIS.

DESIGN FOR A SPOON, &c.

SPECIFICATION forming part of Design No. 22,034, dated December 6, 1892.

Application filed April 25, 1892. Serial No. 430,640. Term of patent 7 years.

To all whom it may concern:

Be it known that I, WILLIAM C. SOMMER, a citizen of the United States, residing at Springfield, in the county of Sangamon and State of Illinois, have invented and produced a new and original Design for a Souvenir Spoon, shown in the accompanying drawing, to which reference is hereby made.

The design consists of certain ornamentation of the bowl, stem, and handle of the spoon, which I will now describe. Within the bowl of the spoon is a miniature representation in relief of the monument erected to the memory of Abraham Lincoln at Springfield, Illinois. The stem of the spoon is ornamented with raised foliated scrollwork, as clearly shown in the drawing. The handle of the spoon is

ornamented with a raised bead extending around the edges and outer end of said handle. On the face of the handle and within the space inclosed by the bead is a miniature representation in relief of the residence at Springfield, Illinois, formerly occupied by Abraham Lincoln.

Having fully described my design in its essential features, what I claim as new, and desire to secure by Letters Patent, is—

The design for a spoon, as herein shown and described.

WILLIAM C. SOMMER.
